UNITED STATES PATENT OFFICE.

ERNEST W. LINDQUIST, OF LAWRENCE, MASSACHUSETTS.

SAVE-ALL.

1,270,422.

Specification of Letters Patent. Patented June 25, 1918.

Application filed March 15, 1918. Serial No. 222,659.

To all whom it may concern:

Be it known that I, ERNEST W. LINDQUIST, of Lawrence, in the county of Essex and State of Massachusetts, have invented 5 certain new and useful Improvements in Save-Alls, of which the following is a specification.

This invention relates to what are known as save-alls for paper pulp. In the process 10 of paper manufacture with what is known as a wet or cylinder machine, a screened cylinder or cylinder mold revolves in a vat and picks up a certain amount of stock which is removed by a couch roll or in some 15 other way. Some of the fine stock passes through the mesh into the inside of the cylinder and as it has a value, it is desirable either to separate it entirely from the water or to remove a certain proportion of water 20 so as to make the stock thicker. This saving process is usually done in a separate machine.

In other paper making processes, it is sometimes desirable to reduce the amount 25 of water in the stock or to thicken it, and this is accomplished in machines known as thickeners.

In the wet or cylinder machine and in the thickener, there is a vat and a screened cylinder revoluble therein, and my invention 30 in general consists in locating an inner cylinder inside the outer cylinder, in providing means for allowing the substantially clear water to run from inside the inner cylinder 35 to the outside of the vat, and in providing means for removing to a point outside the outer cylinder the thicker part of the screened stock which remains on the outside of the inner cylinder. Such stock may be 40 removed entirely from the machine or may be returned directly to the vat to be re-worked. The inner cylinder may or may not have a finer mesh than the outer cylinder.

45 In the drawings, Figure 1 is an elevation from the left of a cylinder machine of my construction with parts of the end of the vat and parts of the heads of the cylinders removed, and some parts shown in diagram. 50 Fig. 2 is generally a view from the direction of the arrows on line 2-2 of Fig. 1, some of the parts being broken to show construction. Figs. 3 and 4 are views of modifications on sections similar to Fig. 2. Fig. 5 is an elevation from the left of the machine shown in Fig. 4. Figs. 6 and 7 are details

of a valve, Fig. 7 being a section on line 7-7 of Fig. 6.

A represents a vat of rectangular shape having a curved inside partition 1 which 60 merges with side 2 of the vat, but at the other side is separated from the side 3 forming a channel 4 through which the stock C enters the vat through pipe B. 5 is the bottom of the vat and 36 and 37 are the ends 65 thereof.

6 and 7 represent the brackets or supports for the bearings 8 and 9 in which, as shown, the supporting means for the outer cylinder F and inner cylinder D are carried. 70

34 is a sleeve revoluble in bearing 8 which carries a gear 35 by which it is driven. Fixed to the inner end of sleeve 34 is one head 50 of outer cylinder F, such cylinder being of any well known skeleton 75 construction having at its opposite end a head 51 and its curved surface 52 being covered with fine-meshed papermaker's wire gauze, all of well known construction. 10-10 represents connecting straps which 80 make the outside cylinder more rigid.

The other head 51 of cylinder F around its center has an annular shoe 53 which fits closely and is revoluble about an annular conduit 17 which forms part of bearing 9 85 and extends through the wall 37 of the vat. Outer cylinder F is therefore revoluble with sleeve 34 and around conduit 17.

As shown in Figs. 1 and 2, annular conduit 17 extends upward at 16 in the form of 90 a tapering hollow bracket and to the top of such bracket is rigidly fixed a conveyer 13, which is shown as in the form of a cylinder with one end closed but with a longitudinal opening at 55 from the bottom of which 95 extends a lip 40 which serves as a doctor blade or scraper, as will be described.

As shown, through conveyer 13 extends a worm 14 whose shaft 38 extends through arm 41 and carries a gear 30 which engages 100 a gear 31 carried on the inner wall of the right head 50 of cylinder F. As bearing 9 and conduits 16 and 17 do not revolve, conveyer 13 and scraper 40 are fixed in position and outer cylinder F revolves around them. 105 Arm 41 is fixed to sleeve 43 fixed to bearing 8 by arm 42 around which sleeve 34 revolves.

The inner cylinder D is shown as of less diameter and shorter than cylinder F and 110 revolves inside conveyer 13, being of such size that scraper 40 will scrape its curved

surface as it revolves. The sleeve 32, concentric with sleeve 34 and inside sleeve 43, carries at its outer end a gear 33 by which it is driven and carries the right-hand head 56 of cylinder D. The other head 61 of cylinder D around its center carries a bearing ring 63 revoluble on a nipple extension 64 of bearing 9. The curved surface 62 of cylinder D is covered with wire paper-maker's mesh which may be finer than that on cylinder F.

Through bearing 9, conduit 17, and nipple 64 extends a clear water conveyer E shown in the form of a pipe with inlets 65 and 66 15 from the inside of cylinder D. I prefer to make the inlets 65, which are nearer the outlet, smaller than those 66 at the other end to equalize the flow and the motion on the surface of the liquid.

20 H represents a couch roll and K the felt apron of any usual form. Cylinders F and D may be driven at any desired speeds and whatever fine stock passes through cylinder F is picked up on the curved surface 62 of inner cylinder D and as it revolves is scraped therefrom by scraper 40 and is carried through conveyer 13 to conductors 16 and 17 and delivered at any point outside the outer cylinder.

25 The worm 14 is shown as a positive means for conveying the stock to a point desired, but it is manifest that other mechanism may be used for this purpose.

I prefer to extend conduit 17 downward 30 at 18 and to connect with it means for returning the stock to the top of the vat shown as comprising a pipe 19 in which revolves a worm 20 whereby the screened stock is delivered at 21 back into the vat.

35 Worm 20 is shown as having a shaft 23 which carries a bevel gear 22 in engagement with another bevel gear 24 revoluble by means of a sprocket 25 connected by chain 26 with sprocket 27 driven by a gear 28 40 which engages a gear 29 carried by and extending around the outside of the left end of cylinder F.

In connection with the doctor blade 40 45 I prefer to use water spraying means inside of the inner cylinder D for the purpose of keeping its meshed surface 62 clean and free. In Figs. 1 and 2, I show a bracket 67 fixed by a set screw 54 to the inner end of nipple 64 and this bracket supports the 55 left ends of spray pipes 68 and 69.

Spray pipe 68 is located parallel with the axis of cylinder D and is in advance of the edge of blade 40 and has holes by which a water spray can be directed under the stock

60 just before it reaches the doctor blade, whereby the cylinder mesh is clean and the work of the blade is assisted.

Pipe 69 is located beyond the doctor blade 40 and is parallel to 68 and has holes by 65 which a spray can be directed from the in-

side on the mesh 62 of cylinder D, whereby after the stock is substantially scraped off by the doctor blade, this spray will clean it still further.

The right ends of pipes 68 and 69 are connected by right angled pipe sections 44 and 45 which serve to support that end and extend radially from a hub 46, as shown in Fig. 6, which forms the right end of clear water conveyer E or is fixed thereto, as 70 shown in Fig. 7.

The spray water inlet pipe 47 is screwed into hub 46 and the ports 48 and 49 communicate from the hub with pipes 44 and 45.

I prefer to provide a two-way valve in 80 hub 46 having a stem 56 with ports 57 and 58 adapted to register with ports 48 and 49 and turnable by rod 59 which extends through pipe 47 in any convenient way, as shown in Fig. 2.

85 By this two-way valve, water can be directed through either spray pipe 68 or 69, through both, or can be cut off entirely, as desired.

The clear water conveyer E and spray 90 water conductor 47 are shown as extending axially through both cylinders. The left end of E is supported in bearing 9, and the right end of 47 may be bent down, as shown at 12 in Fig. 2, and supported 95 thereby or supported in any other suitable manner.

In Figs. 1 and 2, the means to remove the screened stock from the inner cylinder is the doctor blade 40 which may be assisted 100 by spray pipe 68, and the means to convey the screened stock to the outside of the outer cylinder are the conveyer 13, worm 14, and conductors 16 and 17.

In Fig. 3, I show a construction adapted 105 for a thickener or save-all independent of a cylinder machine, in which the vat A may be substantially the same and is shown as having ends 76 and 77.

The spray pipe or pipes, such as 68, and 110 spray pipe water conductor 47, together with the clear water conveyer E are substantially the same as in the first described construction, and the inner cylinder M is similar to D. It has ends 70 and 71 and is supported 115 on ends of sleeves 72 and 73 which extend out through bearings 74 and 75 through walls 76 and 77 and may be supported by suitable bearings in supports 78 and 79. They are shown as driven by a pulley 80 120 fixed to sleeve 72.

The bracket 67 which supports the spray pipe or pipes is fixed to conveyer E by a set screw 54.

125 Instead of a conveyer and worm, however, I show a trough 81 which extends from one side to the other of vat A at a slope and empties into a trough 82. The doctor blade 83 at the edge of trough 81 scrapes the screened stock from the surface of the inner 130

cylinder M and it travels by gravity to outside the outer cylinder and outside the vat.

The outer cylinder L has annular heads 84 from which project flanges 85 which rest 5 inside of and are revoluble in flanges 86 attached respectively inside the ends 76 and 77 of the vat.

On the inner side of flanges 85 are interior gear teeth 87 which are engaged by 10 gears 88 carried by a shaft 89 which extends from end to end of the vat between cylinder M and cylinder L and may be driven by any suitable means, not shown.

To remove the partly screened stock from 15 outer cylinder L, I show a doctor blade 93 which extends from an inclined trough 91 extending from end to end of the vat whereby as the partly screened stock is scraped off, it travels by gravity to the outside of 20 the vat and is shown as dropping into trough 82.

The mesh on inner cylinder M is preferably finer than that on outer cylinder L.

In Fig. 4, I show a construction in which 25 the inner cylinder D and its attachments and connections are similar to D, shown in Figs. 1 and 2, and intermediate cylinder F corresponds with outer cylinder F in those views.

30 Instead of the couch roll H, however, I show an inclined trough arrangement 81 such as is used on cylinders M and L, shown in Fig. 3.

Outside cylinders D and F, I show a 35 cylinder L which is supported inside of the tank and is constructed in the same manner as cylinder L, shown in Fig. 3, and is driven in the same way by interior gear teeth 87 and gears 88. The screened stock 40 is removed from this cylinder by a doctor blade and inclined trough 91 and is delivered into another trough 95.

As shown in Fig. 5, troughs 95 and 82 are bent down as vertical conductors and 45 deliver the screened stock into the same tank T into which conduit 17 delivers. From this tank T the screened stock may be pumped through the medium of the pump 97 wherever desired.

50 It will readily be seen that even more screened cylinders might be used by suitable adaptation of the manner of supporting them and of conveying the screened stock from the outside thereof to the outside of 55 the outer cylinder, preferably outside of the vat.

The clear water conveyer preferably extends out through the axis of the cylinders.

I claim:

60 1. In a save-all for paper stock the combination with a vat, and an outer screened cylinder revoluble therein, of one or more inner revoluble screened cylinders, a clear water conveyer which passes from the inner cylinder to outside the vat, and means to

remove the screened stock from the inner cylinder or cylinders.

2. In a save-all for paper stock, the combination with a vat, and an outer screened headed cylinder revoluble therein, of a shorter inner revoluble screened headed cylinder, an axial clear water conveyer which passes through the inner cylinder and has inlets therefrom, and means to remove the screened stock from the inner cylinder. 75

3. In a save-all for paper stock, the combination with a vat, and an outer screened cylinder revoluble therein, of one or more inner revoluble screened cylinders, a clear water conveyer which passes from the inner cylinder to outside the vat, means to remove the screened stock from the inner cylinder or cylinders, and means to convey the screened stock to outside the outer cylinder. 80

4. In a save-all for paper stock the combination with a vat, and an outer screened cylinder revoluble therein, of an inner revoluble screened cylinder, a clear water conveyer which passes through the inner cylinder and has inlets therefrom, a scraper which engages the inner cylinder and is adapted to remove the screened stock therefrom, and a conveyer from said scraper to convey the screened stock away from the 95 scraper to outside the outer cylinder.

5. In a save-all for paper stock the combination with a vat, and an outer screened cylinder revoluble therein, of an inner revoluble screened cylinder, a clear water conveyer which passes through the inner cylinder and has inlets therefrom, a scraper which engages the inner cylinder and is adapted to remove the screened stock therefrom, a conveyer from said scraper to convey screened stock away from the scraper, and a conduit from the conveyer to the outside of the vat. 100

6. In a save-all for paper stock the combination with a vat, and an outer screened cylinder revoluble therein, of an inner revoluble screened cylinder, a clear water conveyer which passes through the inner cylinder and has inlets therefrom, a scraper which engages the inner cylinder and is adapted to remove the screened stock therefrom, a conveyer from said scraper to convey screened stock away from the scraper, a conduit from the conveyer to the outside of the vat, and means to return the screened stock from the 110 conduit to the vat. 115

7. In a save-all for paper stock the combination with a vat, and an outer screened cylinder revoluble therein, of an inner revoluble screened cylinder, a clear water conveyer which passes through the inner cylinder and has inlets therefrom, a scraper which engages the inner cylinder and is adapted to remove the screened stock therefrom, and a conveyer, including a worm 120 125 130

positively driven by the outer cylinder, from said scraper to convey the screened stock away from the scraper to outside the outer cylinder.

- 5 8. In a save-all for paper stock the combination with a vat, and an outer screened cylinder revoluble therein, of an inner revoluble screened cylinder, a clear water conveyer which passes through the inner cylinder and has inlets therefrom, a scraper which engages the inner cylinder and is adapted to remove the screened stock therefrom, means to spray water on the inner cylinder proximate to and beyond the 10 scraper, and a conveyer from said scraper to convey the screened stock away from the scraper to outside the outer cylinder.

9. In a save-all for paper stock the combination with a vat, and an outer screened cylinder revoluble therein, of an inner revoluble screened cylinder, a clear water conveyer which passes through the inner cylinder and has inlets therefrom, a scraper which engages the inner cylinder and is 15 adapted to remove the screened stock therefrom, means to spray water on the inner cylinder proximate to and beyond the scraper, and a conveyer from said scraper to convey the 20 screened stock away from the scraper to outside the outer cylinder.

10. In a save-all for paper stock the combination with a vat, and an outer screened cylinder revoluble therein, of an inner revoluble screened cylinder, a clear water conveyer which passes through the inner cylinder and has inlets therefrom, a scraper which engages the inner cylinder and is 25 adapted to remove the screened stock therefrom, means to spray water from inside the inner cylinder on its screened surface proximate to and in front of the scraper, and a conveyer from said scraper to convey the 30 screened stock away from the scraper to outside the outer cylinder.

10. In a save-all for paper stock the combination with a vat, and an outer screened cylinder revoluble therein, of an inner revoluble screened cylinder, a clear water conveyer which passes through the inner cylinder and has inlets therefrom, a scraper which engages the inner cylinder and is 35 adapted to remove the screened stock therefrom, means to spray water from inside the inner cylinder on its screened surface proximate to and in front of the scraper, and a conveyer from said scraper to convey the 40 screened stock away from the scraper to outside the outer cylinder.

to spray the water on the inside of the screened surface of the inner cylinder, and a conveyer from said scraper to convey the screened stock away from the scraper to outside the outer cylinder.

11. In a paper stock machine, the combination of a vat, and a revoluble screened cylinder therein, with a fixed spray water pipe which enters the said cylinder axially, a two-way valve therein, two-branch pipes which extend from the two-way valve proximate to and in front of and behind the scraper having holes to spray water on the inside of the screened surface of the said cylinder.

12. In a save-all for paper stock the combination with a vat having oppositely disposed bearings, of a fixed spray water inlet pipe which passes through the center of one bearing, a fixed clear water conveyer which extends out through the center of the other bearing, one or more spray pipes parallel with the clear water conveyer supported thereby and by the spray water inlet pipe, an inner screened cylinder revoluble about the spray water pipes, a sleeve fixed thereto concentric with the spray water inlet pipe and extending out through the vat, driving means at the outer end thereof, a scraper outside of the inner screened cylinder carried in supports fixed to the 75 bearings, a conveyer from such scraper to a point outside the vat, an annular shoe revoluble about one bearing, a sleeve which extends through the other bearing, and an outer screened cylinder fixed to such shoe and 80 sleeve revoluble outside the inner cylinder and the scraper, together with driving means fixed to the outer end of the last named sleeve.

In testimony whereof I have affixed my 85 signature.

ERNEST W. LINDQUIST.
